KENNETH DAVIS, OF ST. BENEDICT, PENNSYLVANIA, ASSIGNOR TO REMBRANDT PEALE, RICHARD PEALE, AND REMBRANDT PEALE, JUNIOR, TRUSTEES

DISINTEGRATING AND CONVEYING MACHINE

Application filed May 12, 1923. Serial No. 638,486.

The invention relates to machines for handling loose materials and more especially to a novel and highly efficient automotive, dirigible machine for disintegrating a mass of material and thereafter conveying away the disintegrated and dislodged material, although the machine will operate equally well on piled loose material.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a top plan of a machine embodying the invention;

Fig. 2 is a rear elevation of the machine of Fig. 1;

Fig. 3 is a central transverse vertical section taken substantially on the line 3—3 of Fig. 1;

Fig. 4 is a transverse longitudinal section taken substantially on the line 4—4 of Fig. 1;

Fig. 5 is an enlarged fragmentary sectional detail of the reversible driving mechanism for the traction means which also constitute the steering mechanism;

Fig. 6 is an enlarged fragmentary vertical section through the drive for the disintegrating and conveying mechanism, taken substantially on line 6—6 of Fig. 1;

Fig. 7 is a fragmentary elevation, with parts in section, of one of the disintegrating and conveying arms;

Fig. 8 is an elevation showing the machine operated by a distant control mechanism;

Fig. 9 is a top plan, partly diagrammatic, of the disintegrating and conveying machine cooperating with a conveying chute;

Fig. 10 is an elevation and transverse section taken on line 10—10 of Fig. 9;

Fig. 11 is a fragmentary side elevation of the conveyor chute;

Fig. 12 is a vertical transverse section taken on line 12—12 of Figs. 9 and 11;

Fig. 13 is a plan, largely diagrammatic, of the double cross conveyor and the disintegrating machine cooperating in a mine room;

Fig. 14 shows the machine operating with a winding mechanism; and

Fig. 15 is a vertical transverse section, substantially like Fig. 4, but showing the bed plate omitted.

The machine herewith exemplarily embodying the invention, in its broader or general features comprises a frame carrying a motor which drives both the automotive mechanism of the machine and also the material handling mechanism thereof. The automotive mechanism comprises two traction wheels, one at either side of the machine.

The steering or directing and manoeuvring of the machine is effected by controlling the action of the motor through the driving connections on the two traction wheels, whereby both wheels may be driven forwardly together, or backwardly together, or one may be driven forwardly and the other backwardly simultaneously therewith, or either wheel may be driven in either direction while the other is at rest.

The controls for the driving connections for effecting the different movements and relations of movements just described are preferably controlled from a distant station, so that the attendant need not necessarily follow the machine, but may remain at one station or place while the machine travels with the work under his guidance. This is effected by a plurality of solenoid-operated clutches in the driving connections between the motor and the traction wheels.

The material disintegrating and conveying mechanism comprises a plurality of material disintegrating and conveying arms, claws, or devices traveling across the front of the machine and engaging and disintegrating a mass of material in front of the ma-

chine and conveying it across and to one side of the machine. At the same time these devices participate in the forward travel of the machine, and thus progressively disintegrate and convey away a mass of materials into 5 which the machine is traveling, the rate of advance of the machine being proportioned, or regulated to the rate of disintegration and conveyance of the disintegrated material by 10 the machine.

15 The disintegrating and conveying arms are mounted on and are driven by an endless chain, which in turn is driven from the motor. The material in this embodiment is conveyed across the machine and delivered 15 at one end thereof.

20 In the preferred form of the machine, the disintegrating and conveying arms do not sweep or travel along the floor, but a platform is employed therebeneath. The platform 25 preferably extends across and in front of the machine and slopes downwardly and forwardly with the front edge on, or just clearing, the floor. The disintegrating arms rest upon and sweep across the platform, and the front ends of the arms extend beyond the platform so as to engage with and disintegrate the material in front of the machine. 30 In this case the material is delivered from the platform at the side of the machine.

35 Cooperating with the machine is a type or structure of automatic conveyor adapted to receive the conveyed material from the traveling disintegrating and conveying machine at all points or places along its travel, without the intervention between the machine and conveyor of manual handling or any other adventitious handling of the material.

40 As embodied, the invention is applied to the transportation, or disintegration and conveyance, and other handling of coal in a mine room. An automatic trough or conduit conveyor extends from the entry longitudinally of the room, almost to the room face, the conveyor being constructed in 45 interchangeable unit sections so that it can be extended as the face of the room advances.

45 At the inner end of the room, contiguous to and extending across the room face, is an 50 open-sided trough conveyor, having also automatically-operating, material conveying mechanism. The disintegrating and conveying machine travels across the room face, disintegrating a mass of shot-down coal and conveying it into the open side of the transverse conveyor continuously as the machine 55 travels across the room face, disintegrating and removing all the material before it and discharging it into the open-sided transverse 60 conveyor, which in turn discharges it into the main conveyor, which discharges it into the entry.

65 Other features of the invention will be first set forth in connection with the following detailed description, but it will be understood

that the foregoing general description and the following detailed description are exemplary and explanatory but are not restrictive of the invention.

Referring now in detail to the embodiment 70 of the invention illustrated by way of example in the accompanying drawings, and referring primarily to the general structure of the machine, a platform or bed 1 is provided upon which all the mechanism is supported, and the forward part of which serves also as a part of the mechanism for conveying away the disintegrated material. The plate 1 is preferably inclined downwardly and forwardly, with its front edge, extending substantially entirely across the machine, in contact with the floor or substantially so, as best appears from Fig. 4. The material disintegrating and conveying arms travel over and across the forward end of the plate 1, as will 80 be later more fully described.

85 Supported on the plate or bed 1 is a motor 2, which motor conveniently serves to drive both the machine itself (with selective controls for the traction means whereby the machine may be steered) and also the disintegrating and conveying mechanism.

90 The traction means, as shown, consists of a pair of broad and heavy wheels, although other forms of traction means may be utilized, such as endless tread traction belts. As embodied, a traction wheel 5 is located at one side of the machine and a similar traction wheel 6 at the other side thereof. Wheel 5 is loosely mounted on a shaft (which is later 100 described) which shaft is journaled in bearings 7 and 8 formed, respectively, on pillars or brackets 9 and 10, carried upon the base plate 1 of the machine. Likewise, traction wheel 6 is loosely mounted on a shaft 15, 105 which shaft is fixedly carried in bearings 11 and 12, formed, respectively, in brackets 13 and 14 mounted on the base plate of the machine. The traction wheels may be provided with calks 16.

110 Referring now to the driving means for the two traction wheels, said means in the present embodiment comprise driving sprocket wheels, engaging with the traction wheels, and selectively disconnectable and reversible 115 driving connections between the motor and sprocket wheels. Thereby the wheels may be driven simultaneously in either direction, or may be driven independently of each other 120 in either direction, or either wheel may be driven in either direction while the other is at rest.

125 As embodied (Figs. 1 to 5), fixed on one end of the motor shaft 20 is a worm 21, meshing with a worm wheel 22, which is fixed on a shaft 23. Shaft 23 is journaled in a long, divided and bifurcated bearing 24, the shaft 23 extending both forwardly and rearwardly from the worm wheel 22, which is located in the central opening in bearing 24 (Fig. 4). 130

At its forward end, shaft 23 is provided with a worm 26, which meshes with a worm wheel 27. Worm wheel 27 (see especially Fig. 5), is mounted loosely upon the end of a shaft 28, and is held in place by collars 18 and 19. Referring now to the driving connections from worm wheel 27 to traction wheel 6, shaft 28 is journaled in a bearing 29, preferably provided with a sleeve 30. Fixed on the other end of shaft 28 is a sprocket wheel 31, which meshes with sprocket teeth or holes 32, formed in the periphery of the traction wheel 6.

A clutch jaw 33 (Figs. 1 and 5) is formed on the hub of the worm wheel 27, and a cooperating clutch jaw 34 is splined on shaft 28 to rotate therewith, while being slideable therealong. Clutch jaw 34 is provided with an annular peripheral groove 35 into which project pins 36 and 37, which pins are carried by a yoked bell-crank lever 38, pivotally supported at 39. At its opposite end 40, the bell-crank lever is pivotally connected to the core of a solenoid 41, mounted upon the machine frame. While all the clutches are shown as being solenoid operated, for distant control it will be understood that they may all be manually operated, if desired.

In the drive from the worm wheel 27 to the traction wheel 5, as embodied, (Figs. 1, 4 and 5) a shaft 50 is journaled in a bearing 51, near the worm wheel, and also in a bearing 52, at the other end thereof. The shaft 50 is centrally socketed to receive the reduced end 53 of the concentric shaft 28, previously described. A clutch jaw 54 is formed on this side of the worm wheel 27. Cooperating therewith is a clutch jaw 55, which is splined on the end of shaft 50 to rotate therewith while being slideable therealong. Pins 56 and 57 are mounted in a yoked lever 59 and project into an annular peripheral groove 58 formed in the clutch jaw 55. Lever 59 is pivotally connected at 60 on the machine frame, and is pivotally connected at 61 to a solenoid 62 mounted on the machine frame.

Fixed to the opposite end of shaft 50 is a sprocket wheel 63, meshing with sprocket teeth or holes 64, which are formed in the periphery of the traction wheel 5. The foregoing mechanism, by the control of the solenoids 41 and 62 will drive both the wheels 5 and 6 together in one direction, or will drive either wheel in one direction independently of the other wheel, that is, irrespective of whether the other wheel is at rest or is being driven in the opposite direction.

Referring now to the mechanism for driving the traction wheels 5 and 6 in the opposite direction, a worm 70 is formed on the rear end of the shaft 23, the worm meshing with a worm wheel 71. Worm wheel 71 is mounted in the same manner, and is connected to the same kind of mechanism, as is shown in Fig. 5, and has already been de-

scribed in connection with the traction drive at the front of the machine. A clutch jaw 72, formed on one side of worm wheel 71, cooperates with a clutch jaw 73, which is mounted on the shaft 74, to rotate therewith but is slideable therealong. Shaft 74 is journaled in a bearing 75, and has fixed to the other end thereof a sprocket wheel 76, which meshes with the sprocket holes 32 in the traction wheel 6. Clutch member 73 is likewise shown as solenoid controlled, and a yoked lever 79 has pins which engage in the peripheral grooves 78 in the clutch member. Lever 79 is pivotally mounted at 80, and is pivotally connected at 81 to the core of a solenoid 82.

On its opposite side, the worm wheel has integral therewith a clutch jaw 88, cooperating with a movable clutch jaw 89. Clutch jaw 89 is mounted upon a shaft 90 to rotate therewith, and is slideable therealong into and out of engagement with clutch jaw 88. Shaft 90 is journaled at 91 and 92 on the machine frame, and may be constructed and connected with the mechanism just described substantially in the same manner as the shaft 50, and as more particularly shown in Fig. 5. Clutch member 89 is also solenoid controlled, a lever 94 having pins engaging with the peripheral annular groove 95 in the clutch member. This lever is pivotally supported at 96, and at 97 is pivotally connected to the core of a solenoid 98. There is fixed to shaft 90 on its opposite end a sprocket wheel 99, meshing with the sprocket holes 64 in the traction wheel 5.

Thus in similar manner the solenoids 82 and 98 may be controlled so that the sprocket wheels 76 and 99 may be caused to drive the traction wheels 5 and 6 together in the opposite direction from the sprocket wheels 31 and 63, or either of the sprocket wheels 5 and 6 can be driven in said direction independently of the other. It will be clear that one traction wheel can be driven in one direction and the other traction wheel in the other direction and the machine may thus be turned pivotally about an axis within the machine itself. In Fig. 8, a distant control for the solenoids is shown which may be the same as, or generally similar to, that shown in my co-pending patent applications Ser. No. 445,701, filed February 17, 1921, patented November 24, 1925, No. 1,562,872; Serial No. 512,396, filed November 2, 1921; and Serial No. 541,122, filed March 4, 1922.

The solenoids controlling the various mechanisms described have circuit connections through a cable 99 and a self-winding and paying out cable mechanism 100 to circuit control device 101, such as is described in my said co-pending applications and need not be described here in detail.

Referring now in detail to the embodied form of the material distintegrating and con-

veying means, a plurality of arms or claws 114, spaced apart in series, and preferably parallelly arranged, travel across the front of the machine as it is advancing into the material. The arms preferably travel in contact with the top of the plate 1, and the points or forward ends of the arms extend beyond the forward edge of the plate 1, whereby they are capacitated especially for digging into and disintegrating the material ahead of the machine and causing it to fall freely upon the platform 1, thence to be swept forward across the machine to the place of delivery by the arms 114.

As embodied, the arms are carried on an endless chain 115, to which the arms are connected in any suitable manner. As shown, plates 116 project from the chain and the arms 114 are pivoted to these plates, respectively, at 117. The chain runs in a guideway comprising a lipped bottom plate 118 and a like top plate 119 and a back spacing and supporting block 120. The arms 114 have an offset shouldered end riding upon the chain guide, and have a lateral projection or tail for controlling and moving the arm and for holding it in its operating position, as later described.

The arms are adapted to move automatically to inoperative position after passing the point of delivery of the material, and to automatically reassume operative position as they again approach the mass of material ahead of the machine; that is, at the right in Fig. 1. As embodied, the arms 114 are pivoted, as stated, at 117, on the chain 115; each arm having its rear end or tail 127 angularly disposed and shaped to ride against a plate 128, which plate projects upwardly from the bed plate 1 and constitutes a positioning and guiding cam track along which the rear end of the disintegrating and conveying arms travel. Plate 128 is also preferably continued upward as a back plate having braces 133 against which the conveyed material is stopped and compelled to travel with the arms to delivery. A back plate 132 also serves a like purpose.

As the rear ends or tails 127 of the arms strike and then ride upon the end of the plate 128, near the right hand end of the machine in Fig. 1, the arm is thereby swung automatically into, and is held in, the operative position. By reason of the engagement of the rear end 127 of the arm with the track 128 until the arm has passed the delivery position (at the left hand end of Fig. 1), the arm is maintained in position to disintegrate and sweep the material before it along the front of the platform 1. As the tail 127 of the arm leaves the plate 128 (near the left hand end of Fig. 1), the arm will rock backwardly and lie approximately parallel to the direction of its travel until it again comes to the forward end of the plate 128, all as shown in Fig. 1.

The arms 114 are preferably somewhat

curved forwardly and outwardly and are preferably provided at the forward end with a claw 130, adapted to dig into the material to be disintegrated. The claws 130 are preferably detachably held in the end of the respective arms by suitable means, such as screws 131.

Referring now to the embodied form of driving means for the disintegrating and conveying mechanism (Figs. 1, 2, 3, and 6), there is provided on the left hand end of the shaft 20 of the motor 2 a coupling 140, which connects the motor shaft to a shaft 141 (upon which shaft the traction wheel 5 is loosely journaled with interposed sleeves 142 and 143 as already briefly mentioned). Fixed to the other end of shaft 141 is a worm 144, meshing with the worm wheel 145, which is fixed on a shaft 146 which shaft is journaled in a bearing 147 on the machine frame.

Fixed also on shaft 146 is a worm 148, which meshes with a worm wheel 149, which is fixed on the upper end of a vertically disposed shaft 150. Shaft 150 is journaled in a bearing 151, carried on a bracket or pedestal 152, mounted on the machine frame. Fixed to the shaft 150, at the bottom end thereof, is a gear pinion 153, meshing with a gear wheel 154. Gear wheel 154 is fixed on the bottom end of a vertically disposed shaft 156, which is journaled in the pedestal 152. A sleeve 157 surrounds shaft 156 and has a flanged upper end resting on the top of pedestal 152, a nut 158 being preferably screw-threaded onto the top end of shaft 156 to hold it in position. Fixed to and concentric with gear wheel 154 is a sprocket wheel 155, which meshes with and drives the chain 115.

The disintegrating and conveying machine previously described is especially capacitated or adapted to operate or cooperate with an automatic conveyor, such as a trough conveyor having reciprocating pusher blades, or equivalent elements, for conveying the loose material along the trough toward the place of delivery, the disintegrating and conveying machine traveling along an open side of the trough, disintegrating and dislodging the material and simultaneously sweeping or delivering the dislodged material into the trough in front of the pusher blades.

In accordance with one feature of the invention a reciprocating trough conveyor is provided especially adapted for working in a mine room in connection with the disintegrating and conveying machine. As preferably constructed, such a conveyor is either L-shaped or T-shaped, with the base of the L having an open side, toward the face of the room, and the T-shaped conveyor having the cross bar or top thereof with an open side toward the face of the room, the main conveyor in either case extending backwardly toward the entry.

In the embodied form (referring now to

Figs. 9 to 13), a trough conveyor is provided having a bottom 170, and upwardly and outwardly inclined sides 171 and 172, the trough and the entire conveying mechanism being constructed in interchangeable sections, whereby the conveyor can be kept, by the successive addition of sections, in substantially uniform relation to the advancing face of the room. As a matter of convenience and preference, the conveyor units will be of a length substantially equal to the depth of the kerf cuts or undercuttings by which the room face is successively advanced, such a conveyor being shown and described and claimed in my copending application Ser. No. 352,928 filed January 21, 1920.

Within the conveyor trough are a plurality of reciprocable and swingable pusher blades 173, which push the material before them as they advance, and swing upwardly and ride over the material as they return to get behind and push forwardly a fresh mass of the loose material within the conveyor. As embodied, the respective blades 173 are fixed to arms 174 and 175, which are pivoted at 176 to a supporting lug or bracket 177. The brackets 177 are fixed to a longitudinally-disposed, reciprocable bar 178, which connects the different pusher blades along the conveyor.

The arms 174 and 175 preferably terminate in a backwardly-extending arm 179, which is provided at its outer end with an upwardly-extending, bifurcated projection 180, which projection straddles the downwardly-projecting part of the reciprocating bar 178. The bar 178 preferably made of two angle irons, bolted together, the bifurcated projection 180 in such case straddling the downwardly-projecting contacting parts of the angle bar, and acting thereagainst as a stop to position the shovel during the forward material-pushing movement thereof.

Suitable guideways are provided, and in the embodied form, a pair of plates 184 and 185, horizontally-disposed and longitudinally-extending, are spaced apart by blocks 186 and are bolted together to a series of supporting brackets or arches 187 by a bolt 189. Brackets 187 in turn are bolted to bracing supports 188, which pass beneath and up either side of the conveyor trough at either end of each section thereof. On the opposite side there is a like construction, the plates 190 and 191 having spacing-blocks 192, which are bolted together by bolts 193, which likewise pass through the bail or support 187.

Supporting and guiding cross-pieces 195 are fastened to the bar or angle irons 178 and run in the guideway just described. These are spaced well apart along the top of the bar 178 to permit free running thereof without binding while furnishing adequate support.

In Fig. 11 the juncture of the interchange-

able sections is shown, the reenforcing frames 188^a and 188^b being bolted both to a single bracket or support 187 for the superposed guiding structure. The guideways are also of unit length and the abutting ends are bolted to, and are supported by, the member 187.

In Fig. 9 the conveyor is shown with the forward end consisting of a transverse or auxiliary conveyor, substantially at right angles to the main conveyor, such transverse portions being substantially parallel to the room face *a* and being spaced therefrom a little more than the depth of a kerf cut or undercutting. The side 199 is open for the entire length of this conveyor as shown in Figs. 9 and 10. In these figures the disintegrating and conveying machine is shown disintegrating the mass *b* of shot-down coal and conveying it into the open side 199 of the conveyor. The reciprocating blades 173 in this part of the conveyor forward the loose coal delivered thereto from the disintegrating and conveying machines into the main conveyor, which in turn conveys it into the entry, where it is delivered into mine cars, or into another conveyor or otherwise conveniently and properly disposed of.

Referring now to the actuating means for reciprocating the pusher blades 173 and their connecting mechanisms, including the reciprocating bars 178, cables 201 and 202 are provided, which are pulled alternately in one direction and then in the other by any suitable mechanism, such as that shown in my copending application Serial No. 512,778, filed November 4, 1921, patented March 17, 1925, No. 1,529,875. The cable 201, as shown, runs around a sheave 203 and around a sheave 204, and is fastened at 205 to the bar 178 of the cross conveyor.

Cable 202 is fastened at 206 to the bar 178 of the main or longitudinally-disposed conveyor. Another cable 208 is fastened at 209 to the bar 178 of the longitudinally-disposed conveyor, and passes around a sheave 210 and around a sheave 211, and is fastened at 212 to the bar 178 of the cross-conveyor. Cable 202 thus draws the pusher blades 173 of the main or longitudinally-disposed conveyor toward the mouth of the room, that is, downwardly in Fig. 9, and draws the pusher blades 173 of the cross-conveyor to the left in Fig. 9. Cable 201 draws the blades 173 of the main or longitudinally-disposed conveyor inwardly towards the face of the room, that is upwardly in Fig. 9, and draws the pusher blades 173 of the cross conveyor toward the right in Fig. 9.

The cable 208 causes the two conveyors to move together, by transmitting the pull of the respective actuating cables 201 and 202 from one conveyor to the other. The sheaves are disposed so that the pusher blades of the two conveyors may cross each other's path suffi-

ciently so that the material will be delivered fully and promptly from the cross conveyor into the main conveyor.

The arrangement in Fig. 13 of the T-shaped conveyor, which will be used only in unusually wide work, is substantially the same as that already described except that the cross conveyor is longer and the main conveyor is located medianly, and preferably centrally thereof, the cross conveyor feeding thereto from both sides. In Fig. 9 a mass of shot-down and only slightly disintegrated coal is indicated by *b*, and several positions of the disintegrating and conveying mechanism completely disintegrating and conveying it away are diagrammatically indicated in the figure.

By the combined mechanism just described the shot-down coal, which usually is only partly disintegrated, is rapidly and easily completely disintegrated without being unnecessarily pulverized or broken up, and is conveyed away without manual handling of any kind, and avoiding the usual tedious difficult and costly labor of completely disintegrating the material.

In Fig. 14, means are shown whereby the disintegrating and conveying machine is impelled forwardly to its work by a winding action in place of, or in addition to, its tractive efforts. In the embodied form thereof, jacks 222 are set up, and cables 223 are anchored thereto and are fastened to the tractor wheels 5 and 6 in a suitable manner, as by a hook 224 passing into openings in the tractor wheels, the cables then being wound about the tractor wheels like drums.

In Fig. 15 a transverse section is shown of the disintegrating and conveying machine without the bed plate 1 being extended so as to constitute a platform along which the disintegrated material is conveyed to delivery. As embodied, the arms 114, propelled by the chain 115 sweep along the floor in front of the machine and push the material along the floor in the same manner as has been described in connection with the machine wherein the plate or bed extends beneath the arm.

It will be clear that the machine could be employed merely for conveying the material without first disintegrating it, and the description and claims will be so understood. This, however, would be merely utilizing the machine only to a part of its capacity or capability. In such case, the arms 114 would not necessarily extend beyond the front edge of the bed plate 1.

The invention in its broader aspects is not limited to the specific mechanisms shown and described but departures may be made therefrom within the scope of the accompanying claims without departing from the principles of the invention and without sacrificing its chief advantages.

65 What I claim is:—

1. A material handling mechanism including in combination a conveyor positioned on the mine floor and having an open side extending across the face of a mine room and receiving the coal close to the mine floor, and a material conveying machine traveling along between the conveyor and the room face and conveying dislodged material along the mine floor and discharging it directly into the conveyor continuously along the length of its open side.

2. A material handling mechanism including in combination a conveyor resting on the mine floor and having an open side extending across the face of a mine room for receiving coal substantially at the level of the mine floor, and a material disintegrating and conveying machine traveling alongside the open side of the conveyor, said machine having horizontally extending scraper elements traveling in a horizontal endless path, for disintegrating the material and thereafter pushing it laterally and discharging it directly onto said conveyor.

3. A material handling mechanism including in combination a cross conveyor resting on the mine floor and having an open side extending across the face of a mine room and receiving the coal close to the mine floor, a material conveying machine traveling along between the conveyor and the room face for conveying dislodged material in a horizontal path and discharging it directly into the conveyor continuously along the length of its open side, and a main conveyor extending along the room and receiving the material from said cross conveyor and conveying it to the entry.

4. In a machine of the character described, rotatable driving and supporting elements, a bed plate carried by said elements and underslung therefrom so as to be below the axes of the driving and supporting elements, and material disintegrating and conveying members traveling across the front of the machine for breaking up and conveying away material in front thereof and discharging it immediately at the front and side of the machine.

5. In a machine of the character described, rotatable driving and supporting elements, a bed plate at the front of the machine, supported by and underslung from said elements so as to be below the axes of said elements, and substantially at the floor level, and material disintegrating and conveying members traveling on the bed plate, for breaking up and carrying away material in front of the machine and discharging it immediately at the front and side of the machine.

6. In a machine of the character described, rotatable driving and supporting elements, means for driving said rotating elements together or independently, a bed plate carried

by said elements and underslung therefrom so as to be below the axes of the driving and supporting elements, and material disintegrating and conveying members traveling across the front of the machine for breaking up and conveying away material in front thereof and discharging it immediately at the front and side of the machine.

7. In a machine of the character described, 10 a bed plate, rotatable driving and supporting elements, mounted within the outer edges of the bed plate so that the bed plate extends to the front and rear of said rotatable elements, the bed plate being underslung from said rotatable elements so as to lie below the axes of 15 said elements, and material conveying and disintegrating members traveling on the bed plate, for breaking up and carrying away material in front of the machine, said members being foldable to inactive position during 20 part of their travel.

8. A material handling mechanism comprising in combination a bed plate extending across the front of the machine, material disintegrating and conveying elements movable 25 successively across the front of the machine, and selectively controlled power driven means for forcing either end of the front edge of the bed plate into the material.

30 9. A material handling mechanism comprising in combination a bed plate extending across the front of the machine, material disintegrating and conveying elements movable across the front of the machine and around 35 the machine in an endless path, said elements being folded to inactive position during part of the travel, and power driven means for forcing the front edge of the bed plate bodily into the mass of material, or for forcing 40 either end of the front edge into the material.

10. A material handling mechanism comprising in combination a low, flat frame, traction devices at either side of the frame, means for operating the traction devices, a series 45 of horizontally extending arms traveling around the frame in a substantially horizontal plane and in an endless path and projecting forwardly, substantially horizontally and close to the floor from the front of the 50 machine on the front reach of the path, and arranged to discharge the material at one side of the frame immediately at the end of the front reach and at the side of the machine.

11. A material handling mechanism comprising in combination a low, flat frame, traction devices at either side of the frame, means for operating the traction devices, independently or together, a series of horizontally extending arms traveling in a substantially 55 horizontal plane around the frame in an endless path projecting forwardly from the front of the machine and close to the floor, arranged to discharge the material at one side of the frame.

12. A machine for disintegrating and con-

veying material, including in combination means including a series of spaced apart, 60 parallelly arranged arms constituting the sole disintegrating and conveying devices, the arms extending forwardly from the machine, 70 in a substantially horizontal plane and close to the floor and traveling across the front of the machine, the entire path of travel of the arms being substantially in a single plane, 75 and means for traveling the arms, said machine comprising a low frame of relatively great width and little length and adapted to contain the driving means for the arms and traction devices.

13. A machine for disintegrating and conveying material, including in combination, 80 the machine being low and relatively very wide across and very short from front to rear, an endless carrier traveling in an oblong path on the machine, a series of spaced apart arms attached to the carrier and adapted to extend forwardly close to the floor, and in a substantially horizontal plane from the front of the machine to disintegrate 85 the material and convey it across the front of the machine and discharge it at the side, means for driving the carrier, and means for traveling the machine forwardly, including traction devices at either side of the machine

90 independently operable to steer the machine. 95

14. A low automotive machine for disintegrating and conveying away previously dislodged material including in combination a general frame relatively short from front to rear and relatively very wide from side to side, a flexible carrier traveling in an approximately oblong path with the long direction across the machine, a series of spaced apart disintegrating and conveying arms fixed to the carrier and extending in a substantially 100 horizontal plane from the front of the machine and close to the floor on the front reach of the carrier, means for driving the carrier and means for traveling the machine forwardly. 105

110

15. A low automotive machine for disintegrating and conveying away previously dislodged material including in combination a general frame relatively short from front to rear and relatively very wide from side to side, a flexible carrier traveling in an approximately oblong path with the long direction across the machine, a series of spaced apart disintegrating and conveying arms fixed to the carrier and extending in a substantially 115 horizontal plane from the front of the machine and close to the floor on the front reach of the carrier, means for driving the carrier, and means for traveling the machine forwardly including a traction device at either side of the machine and connections whereby the traction devices may be independently driven to steer the machine. 125

16. A material disintegrating and conveying machine including in combination a low, 130

main frame of relatively great breadth and little length, means for traveling the machine in a direction transverse to the greater dimension, and independently operable disintegrating and conveying means mounted to travel in a substantially horizontal plane around said frame.

17. A material disintegrating and conveying machine including in combination a low, main frame of relatively great breadth and little length, means for traveling the machine in a direction transverse to the greater dimension, and a series of successively operating disintegrating and conveying devices extending substantially horizontally and traveling in a substantially horizontal plane in a direction parallel to said greater dimension.

18. A material disintegrating and conveying machine including in combination a low, main frame of relatively great breadth and little length, and disintegrating and conveying means acting on the material through a substantially horizontal path substantially equal in length to said greater dimension.

19. A material disintegrating and conveying machine including in combination a low, main frame of relatively great breadth and little length, and disintegrating and conveying means acting on the material through a substantially horizontal path close to the floor and substantially equal in length and parallel to said greater dimension.

20. A mechanism for removing shot down material including in combination an automotive machine having a low compact frame of relatively great breadth and relatively small length, means for advancing the machine broadside into a pile of shot down material, a series of travelling disintegrating and conveying devices mounted to travel along the front of the machine frame, and means for moving said devices into the pile of material and broadside of the machine to scrape material in a straight line to discharge.

21. A mechanism for removing shot down material including in combination an automotive machine having a low compact frame of relatively great breadth and relatively small length, means for advancing the machine broadside into a pile of shot down material and means for conveying material in a straight horizontal direction broadside of the machine from the pile to discharge at the same level.

22. A disintegrating and conveying machine for removing shot-down material at a mine face and particularly adapted for use in low-seam-mines, including in combination a low compact frame containing driving and traction-operated travelling mechanism, a series of material disintegrating and conveying devices adapted to travel along the frame and just above the mine floor for disintegrating material and scraping it across the front of the frame, and means for travelling the

machine substantially perpendicularly to the direction of conveyance of the disintegrated material and means for selectively varying the speed of different parts of the travelling mechanism to steer the machine over the mine floor to advance the machine horizontally in any given direction.

23. A disintegrating and conveying machine for removing shot-down material at a mine face and particularly adapted for use in low-seam-mines, including in combination a low compact frame containing driving and travelling mechanism, a series of material disintegrating and conveying devices adapted to travel along the frame and just above the mine floor for disintegrating material and scraping it along the mine floor across the front of the frame, and means for travelling the machine substantially perpendicularly to the direction of conveyance of the disintegrated material, said disintegrating and conveying devices being adapted to deliver the material at one side of the machine to a conveyor at the same level.

24. A disintegrating and conveying machine for removing shot-down material at a mine face and particularly adapted for use in low-seam-mines, including in combination a low compact frame of relatively great breadth and little length containing driving and travelling devices, a series of material disintegrating and conveying claws adapted to travel across the relatively wide front edge of said frame, and means for advancing the front edge of the frame into a pile of material whereby the claws project into and underly the material and operate upon a relatively wide face of the pile to scrape the material laterally as the machine advances.

25. A disintegrating and conveying machine for removing shot-down material at a mine face and particularly adapted for use in low-seam-mines, including in combination a low compact frame of relatively great breadth and little length containing driving and travelling devices, a series of material disintegrating and conveying claws adapted to travel across the relatively wide front edge of the frame into a pile of material whereby the claws project into and underly the material and operate upon a relatively wide face of the pile, said claws being adapted to deliver the material substantially at the level of the mine floor.

26. A disintegrating and conveying machine for removing shot-down material at a mine face and particularly adapted for use in low-seam-mines, including in combination a low compact frame of relatively great breadth and little length containing driving and travelling devices, a series of material disintegrating and conveying claws adapted to travel across the relatively wide front edge of said frame, and means for advancing the front edge of the frame into a pile of mate-

rial whereby the claws project into and underly the material and operate upon a relatively wide face of the pile and means for steering and controlling the operation of the machine from a distant station.

5 27. A mechanism for removing shot-down material at a mine face including in combination a low, compact frame of relatively great breadth and little length, means for progressing the wide front of the machine into a pile of shot-down material, material-disintegrating and conveying means comprising a plurality of arms extending substantially horizontally from the front of the machine and lying close to the mine floor, and means for moving said arms across the front of the machine to disintegrate material in the path of advance of the machine and to scrape said material across the mine floor to dis-
10 charge laterally of the advancing machine.

15 In testimony whereof, I have signed my name to this specification,

KENNETH DAVIS.
